UNITED STATES PATENT OFFICE.

WINFIELD YOST, OF CHICAGO, ILLINOIS.

DRAFT-RIGGING FOR RAILWAY-CARS.

No. 895,062.

Specification of Letters Patent.

Patented Aug. 4, 1908.

Application filed January 14, 1905. Serial No. 241,079.

To all whom it may concern:

Be it known that I, WINFIELD YOST, a citizen of the United States, residing in Chicago, in the county of Cook and State of Illinois, am inventor of certain new and useful Improvements in Draft-Rigging for Railway-Cars, of which the following is a specification.

My invention relates to that class of draft-rigging having draft lugs secured to the draft timbers, follower-plates movably mounted between and in operative engagement with such draft lugs, spring mechanism intermediate such follower-plates, and lever mechanism operatively connected with the draw-bar and adapted to yieldingly engage the draft lugs.

The principal object of my invention is to provide a simple, economical and efficient draft-rigging for railway cars.

A further object of the invention is to provide in a draft-rigging for railway cars having spring mechanism for forming a yielding connection between the draw-bar and the draft timbers, suitable lever mechanism for yieldingly connecting the draw-bar mechanism with the draft lugs or draft timbers so as to relieve the spring mechanism of a portion of the load.

A further object of the invention is to provide in a draft-rigging for railway cars suitable spring and lever mechanism for yieldingly connecting the draw-bar with the draft timbers whereby the initial application of force will meet with a comparatively light and yielding resistance and the continued application of force to move the car in either direction will meet with a constantly increasing degree of yielding resistance without at any time becoming actually rigid, and whereby the recoil, when the force is removed, is reduced to a minimum.

A further object is to provide suitable means for yieldingly connecting the draw-bar directly with the draft lugs by means of lever mechanism adapted to receive the strain or force applied in moving the car in either direction, and spring mechanism so operatively connected with the lever mechanism as to increase the resistance of the lever to the movements of the draw-bar as the application of force is continued.

Other and further objects of the invention will appear from an examination of the drawings and the following description and claims.

The invention consists of features, combinations and details of construction hereinafter described and claimed.

In the accompanying drawings—Figure 1 is a plan view of a draft-rigging constructed in accordance with my improvements and connected with the draft timbers of a railway car; Fig. 2 a central sectional elevation taken on line 2 of Fig. 1 looking in the direction of the arrow; and Fig. 3 a transverse elevation in detail taken on line 3 of Fig. 1 looking in the direction of the arrow, showing the arrangements of the lever mechanism.

In constructing a draft-rigging in accordance with my improvements I provide cheek-plates *a* which are secured to the draft sills *b* of a car in any ordinary and well known manner, each being provided with draft lugs *c*, *d*, *e* and *f*, lower flange or guide-portions *g* being secured to the lower edges of the cheek-plates forming tracks for supporting and guiding the levers and followers hereinafter described. Suitable upper flanges, not shown, are provided at the upper edges of the cheek-plates for preventing the displacement of the parts in operation. The upper flanges may be integral with the cheek-plates and the lower flanges secured to the cheek-plates by means of bolts *h*.

A front follower-plate *l* and rear follower-plate *j* are slidably mounted between the cheek-plates and between the draft lugs *d* and *e*, coil-springs *k* and *l* being mounted intermediate such follower-plates so as to hold them in yielding engagement with levers hereinafter described and form a yielding resistance to the movement of such levers and the draw-bar with relation to the draft timbers. A draw-bar *m* and coupler *n* are mounted in the car frame in any ordinary and well known manner, and a tail strap or yoke *o* is secured to the draw-bar by means of bolts *p* and suitable shoulder portions *q* upon the end of the draw-bar in any ordinary or known manner.

Two sets of crossed levers each consisting of oppositely movable levers *r* and *s* are arranged between the respective follower-plates and the tail strap or draw-bar yoke at opposite ends thereof, as shown in Figs. 1 and 2. Each of these levers is provided with an end portion *t* in sliding engagement with the adjacent cheek-plate and movable into engagement with the draft lugs, the inner ends *u* of each of such levers being in sliding engagement with the outer face of the adja-

cent follower-plate. The tail-strap or draw-bar yoke is provided at each end with a lever engaging inner portion *v* having contour surfaces *w* in engagement with the levers between the outer and inner ends thereof, and the inner end of each lever is provided with a stud *y* in engagement with the upper surface of the next adjacent lever in crossed relation thereto. The lugs *y* may preferably be formed on both sides of the levers *r* and *s* in order that these parts may be interchangeable, although it is obvious that when assembled only one of the lugs *y* on each lever will contact with the cooperating lever. By widening or narrowing the contour surface portion of the yoke the leverage can be regulated and the degree of resistance of the levers to the movement of the draw-bar modified as desired.

In operation the force applied for pulling the car or moving it to the left, as shown in Fig. 1, will cause the contour surfaces *w* of the tail strap or yoke to engage the levers *r* and *s* at the right of the figure moving them and the rear follower-plate forward or to the left of the figure against the tension of the springs until the outer ends of the levers come in contact with the draft lugs *d*. During the movement of the levers against the tension of the springs to the point where their outer ends engage the draft lugs such movement and the movement of the draw-bar is resisted only by the tension of the springs and the friction of the outer ends of the lever against the cheek-plates and the tension of the springs is of course comparatively light and yielding at the initial application of force and increases in rigidity rapidly as the application of force continues. It will also be noted that the springs form substantially the only means of connection between the draw-bar and the car or draft lugs until the outer ends of the levers come in contact with the draft lugs, and that up to this point the connection afforded by the springs is much more yielding than after the levers engage the draft-lugs. When the levers come in contact with the draft lugs the continued application of force in the same direction will cause the levers to rock upon the contour or engaging surface of the tail strap or yoke. Their inner ends move forward with the engaged follower-plate against the tension of the springs and their outer ends form a yielding connection between the draw-bar or tail strap and the draft lugs. The pulling strains are then no longer entirely sustained by the spring mechanism but are yieldingly communicated from the draw-bar to the draft lugs through the medium of the levers so as to minimize the shocks received in operation. The contour surfaces are so proportioned that the movement of the draw-bar forward, after the outer ends of the levers come into contact with the

draft lugs, will cause the point of contact to recede from the inner end of the levers and approach nearer to the outer ends thereof, thus throwing an additional proportion of the pulling strains upon the levers and relieving the springs to that extent, at the same time causing the resistance to the movement of the draw-bar to increase rapidly and at an increasing ratio as the application of force is continued. The springs to be used in combination with the lever mechanism, as above described, are not required to be of sufficient strength to bear the entire pulling strains, but need only be sufficiently strong to bear the portion of the strains communicated to them through the lever mechanism and the initial shocks or strains. The increased tension of the springs as they are compressed serves to increase the rigidity of the connection between the levers and the draw-bar and draft lugs without at any time making such connection actually rigid. In this device a much greater force can be applied to the draw-bar than would be sufficient to entirely compress the springs and yet their perfect flexibility is not affected, and the full value of the springs is at all times obtainable.

By arranging the studs *y* upon the inner ends of the levers so that they come in contact with the next adjacent crossed levers, as shown in Fig. 1, the movement of the levers to compressing position, before their outer ends come in contact with the draft lugs, is rendered possible without greatly increasing the frictional resistance between the lever and the cheek-plates, and the return movements of the levers to initial or releasing position is also facilitated. In operation the follower-plates are slightly flexible and the levers are in engagement therewith when their outer ends are in initial position or against the outer lugs *c* or *f*. By this means the shocks are received by both the outer lugs and those which engage the follower-plates. In other words, the force applied to move the draw-bar forward to the left in Fig. 1 is received by the levers shown at the right of the figure and communicated through the medium of the follower-plates and springs to the levers at the left of the figure and to both the lugs *e* and *f*, and vice versa. This is rendered possible by means of the flexibility of the follower plate which permits part of the force to be communicated to the outer lugs which are engaged by the levers when such levers have reached their limit of compressibility by means of the studs *y* coming into engaging position so as to prevent further compression of the levers. All shocks received by the draw-bar in either direction are thus yieldingly resisted and injury to the draft timbers and car structure is prevented.

The arrangement and mode of operation of the lever mechanisms on both sides of the

follower-plates and springs is substantially identical and the description of one set of such levers and its mode of operation applies equally to both and is sufficient to enable the device to be understood by those skilled in the art.

I claim:

1. In a draft-rigging for cars, the combination of draft lugs secured to the draft sills of a car, follower-plate mechanism, a coupler, a draw-bar operatively connected with the coupler and follower-plate mechanism, lever mechanism in engagement with the follower-plate mechanism and draft lugs, forming a yielding connection between the draw-bar and the draft lugs engaged by such lever mechanism.
2. In a draft-rigging for cars, the combination of draft lugs secured to the draft sills of a car, follower-plate mechanism, a coupler, a draw-bar operatively connected with the coupler and follower-plate mechanism, lever mechanism in engagement with the follower-plate mechanism and draft lugs, forming a yielding connection between the draw-bar and the draft lugs engaged by such lever mechanism, and means for holding the follower-plate mechanism in yielding engagement with the lever mechanism.
3. In a draft-rigging for cars, the combination of draft lugs secured to the draft sills of a car, follower-plate mechanism, a coupler, a draw-bar operatively connected with the coupler and follower-plate mechanism, lever mechanism in engagement with the follower-plate mechanism and the draft lugs forming a yielding connection therebetween, and spring mechanism in engagement with the follower-plate mechanism.
4. In a draft-rigging for cars, the combination of draft lugs secured to the car structure, front and rear follower-plates, a draw-bar, and lever mechanism in engagement with such follower-plates and draft lugs, and forming a yielding connection therebetween.
5. In a draft-rigging for cars, the combination of draft lugs secured to the draft sills of a car, front and rear follower-plates, a draw-bar, a yoke secured to such draw-bar, and lever mechanism mounted between the yoke and follower-plates, and movable into and out of engagement with the draft lugs.
6. In a draft-rigging for cars, the combination of draft lugs secured to the draft sills of a car, front and rear follower-plates, a draw-bar, a yoke secured to such draw-bar, lever mechanism mounted between the yoke and follower-plates and movable into and out of engagement with the draft lugs, and spring mechanism mounted intermediate the follower-plates for holding them yieldingly in engagement with the lever mechanism.
7. In a draft-rigging for cars, the combination of cheek-plates secured to the draft sills of a car and provided with draft lugs,

follower-plates mounted between such cheek-plates and movable into and out of engagement with such draft lugs, lever mechanism in engagement with the cheek-plates and follower-plates, and spring mechanism mounted upon the side of the follower-plates opposite the lever mechanism for holding the follower-plates yieldingly in engagement with such lever mechanism.

8. In a draft-rigging for cars, the combination of cheek-plates secured to the draft sills of a car and provided with draft lugs, follower-plates mounted between such cheek-plates and movable into and out of engagement with such draft lugs, lever mechanism in engagement with the cheek-plates and follower-plates, spring mechanism mounted upon the side of the follower-plates opposite the lever mechanism for holding the follower-plates yieldingly in engagement with the lever mechanism, a draw-bar, and a yoke connected with such draw-bar and operatively connected with the follower-plates and spring and lever mechanism.

9. In a draft-rigging for cars, the combination of draft-lugs secured to the draft-sills of a car, follower-plates movable into and out of engagement with such draft-lugs, spring mechanism mounted in engagement with the follower-plates, lever mechanism mounted in engagement with the follower-plates and movable into and out of engagement with the draft-lugs, a draw-bar, and means for connecting such draw-bar with the lever mechanism.

10. In a draft-rigging for cars, the combination of a coupler, a draw-bar secured thereto, and lever mechanism operatively connected with such draw-bar and with the car and provided with means for increasing and diminishing the relative length of the lever arms for affording an increasing yielding resistance to the movement of the coupler and draw-bar with relation to the car.

11. In a draft-rigging for cars, the combination of a coupler, a draw-bar connected with such coupler, and spring and lever mechanism operatively connected with the draw-bar and car and provided with mechanism in engagement with such lever mechanism at shifting points between the ends thereof adapted to change the relative length of the lever arms for providing an increasing yielding resistance to the movement of the coupler and draw-bar with relation to the car.

12. In a draft-rigging for cars, the combination of a coupler, a draw-bar secured thereto, spring and lever mechanism operatively connected with the car structure, and a draw-bar yoke secured to the draw-bar and in engagement with the lever mechanism movable toward and from the opposite ends of such levers and adapted to increase the resistance of the lever mechanism to the

movement of the draw-bar and coupler with relation to the car structure.

13. In a draft-rigging for cars, the combination of cheek-plates provided with draft-lugs and secured to the draft-sills of the car, follower-plates mounted between such cheek-plates and movable into and out of engagement with the draft lugs, spring mechanism mounted between such follower-plates, a draw-bar, a yoke secured to such draw-bar, and a set of levers mounted inside of each end of the yoke each consisting of a plurality of crossed levers in engagement with the yoke, having their inner ends in engagement with the adjacent follower-plate and their outer ends movable into and out of engagement with the draft lugs.

14. A draft-rigging comprising differential levers and an interposed spring, the levers being arranged to vary the effective length of the lever arms as the strain of buffing or draft increases.

15. A draft-rigging having differential levers projecting outwardly beyond the line

of the draw-bar and having spring mechanism.

16. A draft-rigging having differential levers projecting outwardly beyond the line of the draw-bar and having spring-mechanism interposed between them.

17. A draft-rigging having differential levers and a yoke, said levers projecting outwardly beyond the yoke and having spring mechanism interposed between them.

18. A draft rigging comprising draft springs, levers at each end of said draft springs, a yoke surrounding said springs and levers, stops adapted to engage the outer ends of said levers, said stops being so disposed as to permit said levers to move bodily during the initial movement of said yoke, but causing said levers to turn upon said stops as fulcrums during the continued movement of said yoke.
